UNITED STATES PATENT OFFICE.

JAMES MILLER SHEPARD, OF FINDLAY, OHIO.

PUMP.

SPECIFICATION forming part of Letters Patent No. 792,081, dated June 13, 1905.

Application filed August 17, 1904. Serial No. 221,067.

To all whom it may concern:

Be it known that I, JAMES MILLER SHEPARD, a citizen of the United States, residing at Findlay, in the county of Hancock and State of Ohio, have invented a new and useful Pump, of which the following is a specification.

This invention relates to improvements in that class of pumps wherein fluids such as compressed air, gas, or the like are employed as a direct agent for effecting the elevation of liquids.

The prime object is to provide mechanism of a simple nature that will bring the air or driving fluid into coaction with the water or liquid to be elevated, so that the force of the former will be very effectively utilized on the latter, a continuous flow of the liquid being secured with a comparatively small expenditure of force, the submergence being comparatively slight, and the construction being such that should the occasion arise the pump complete can be readily removed and replaced without the necessity of pulling the well tubing or casing.

In the accompanying drawings, Figure 1 is a side elevation of a well with the improved pump structure therein. Fig. 2 is a longitudinal sectional view, on an enlarged scale, through the lower portion of said well. Fig. 3 is a cross-sectional view, on an enlarged scale, on the line 3-3 of Fig. 2. Fig. 4 is a similar view on the line 4-4 of Fig. 2. Fig. 5 is a view in elevation of the pump-body. Fig. 6 is a sectional view, on an enlarged scale, through the head. Fig. 7 is a side elevation of a slightly-modified form of head, and Fig. 8 is a top plan view thereof.

Similar reference-numerals indicate corresponding parts in all the figures of the drawings.

In the embodiment illustrated in the first six figures a barrel 9 is employed, having at its lower end an inlet-strainer 10, connected to the lower end of said barrel by a coupling 11, having a bore 12 therethrough and a tapering seat 13 in the upper end. A standing valve member is employed comprising a plug 14, the lower end of which is tapered and adapted to fit snugly in the seat 13, said plug

carrying a depending tube-section 15, that extends downwardly through the bore 12 of the coupling 11, and preferably into the strainer 10. The plug 14 is threaded into the lower end of a tubular casing 16, and supported on the upper end of said plug is a valve-cage 17, located within the tubular casing 16 and containing a ball-valve 18, coöperating with a seat 19, held within the cage upon the upper end of the plug. The said cage is maintained in place by means of an annular shoulder 20, formed within the lower portion of the tubular casing 16 and bearing upon a shoulder formed on the cage, the lower portion of said cage thus being clamped between the shoulder 20 and the upper end of the plug 14, all of which will be apparent by reference to Fig. 2. The casing 16 forms a liquid-chamber 21, the inlet to which is controlled by the valve 18. The upper end of this chamber is defined by a head 22, the lower portion of which is threaded into the upper end of the tubular casing, said head also fitting snugly within the barrel. Liquid-discharge openings 23 extend upwardly through the head 22, communicating with the chamber 21 at their lower ends and at their upper ends communicating with upwardly-extending nozzles 24 in the form of tubes, that are preferably threaded into the upper end of the head and may be inclined inwardly, as shown. The openings 23 are arranged in an annular series about a central bore 25 in the head, the upper and lower portions of said bore being threaded. A tube 26 is screwed into the lower end of the bore and depends within the liquid-chamber 21. The lower end of this tube is closed by a plug 27, and said tube forms a fluid-chamber 28. A fluid-supply pipe 29 extends longitudinally within the barrel and is screwed into the upper end of the bore 25, said pipe thus communicating with the fluid-chamber. The pipe extends to the top of the well, where the tubing is provided with a suitable offset coupling 30, having an upstanding nozzle 31, through which the pipe projects, as shown in Fig. 1, said pipe leading from any suitable source of fluid under pressure. The head 22 is furthermore provided with an annular series of 100

fluid-outlet openings 32, communicating at their lower ends with the fluid-chamber and terminating at their upper ends in discharge-orifices, one of these orifices being preferably located between each pair of nozzles 24, as shown in Fig. 3, but being disposed below the discharge ends of said nozzles, as will be apparent by reference to Fig. 2.

The operation of the pump may be briefly described as follows: Air or other suitable fluid under pressure admitted through the pipe 29 will pass downwardly into the chamber 28 and escape through the outlets 32 longitudinally of the nozzles. Passing the ends of said nozzles with considerable force a vacuum will be formed therein, which will be supplied with liquid drawn through the lower valved inlet of the liquid-chamber 21 and thence injected or jetted upward through said nozzles into tubing. The force of the discharging fluid is sufficient to elevate the liquid continuously ejected from the nozzles above the outlets 32, so that a continuous stream is discharged from the well, and the peculiar dispositoin of the nozzles and air and fluid outlets secures an effective operation of the pump and a thorough utilization of the force of the fluid employed for elevating the liquid. Moreover, in this structure no back pressure can take place, as the only discharge of the elevating fluid is in an upward direction, and there are no joints in the fluid-supplying means which cannot be made fluid-tight to prevent the escape of the ejecting means in the wrong direction. It will, furthermore, be observed that the head is secured to the supply-pipe and that the standing valve member is connected to said head by the tubular casing 16. Therefore if it becomes desirable or necessary to remove the pump all that is required is to elevate the supply-pipe 29, whereupon the pump in its entirety is carried upwardly, and thus removed without the necessity of pulling the well-tubing.

It is to be understood that the invention is not limited to the specific details shown and described above, but that various changes in the shape, size, proportions, and minor details of construction may be made. As an example of this, attention is invited to Figs. 7 and 8, where a slightly-modified form of head is illustrated. The fluid-feed pipe is shown at 29^a and is secured in the usual manner to the head 30^a, said head carrying the depending tube 31^a, forming an air-chamber. The liquid-discharge nozzles 32^a are arranged about the pipe 29^a and have their intermediate portions inset, as shown at 33^a, their upper ends extending in a substantially vertical direction. At this point it is desired to state that the nozzles may be changed as to size, number, and disposition without in any manner departing from the spirit of the invention.

The fluid-discharge orifices 34^a are also ar-

ranged about the supply-pipe 29^a, and in this construction one of said orifices is located in the space between the adjacent nozzles.

Having thus described my invention, what I claim as new, and desire to secure by Letters Patent, is—

1. In a pump, the combination with a barrel, of a head located therein and having an orifice in its top for the escape of fluid under pressure, a liquid-discharge nozzle carried by the head, said nozzle projecting above the orifice and terminating within the barrel, and means for supplying fluid under pressure to the orifice. 75

2. In a pump, the combination with a barrel, of a fluid-supply pipe extending longitudinally down through the barrel, an upwardly-extending liquid-discharge nozzle located longitudinally alongside the pipe and having its upper end communicating with and terminating in the barrel, and means connected to the lower end of the pipe for directing an upward jet of fluid under pressure into the barrel and longitudinally alongside the nozzle, said means being located in the barrel and having an orifice extending longitudinally of the barrel and communicating with the supply-pipe and also communicating with the barrel below the upper end and at one side of the nozzle. 90

3. In a pump, the combination with a barrel, of a head extending across the barrel, an upwardly-extending liquid-discharge nozzle having its upper end communicating with and terminating in the barrel, and means for directing an upward jet of fluid under pressure into the barrel and longitudinally alongside the nozzle, said means including an orifice formed in the head longitudinally of the barrel and having its upper discharge end terminating below the upper end of the nozzle. 100

4. In a pump, the combination with a barrel, of a head located within the barrel and having a liquid-discharge opening therethrough, a nozzle secured to the head and projecting above the same, said nozzle communicating with the liquid-discharge opening, said head also having a fluid-discharge opening, and a pipe extending longitudinally into the barrel and connected to the head, said pipe communicating with the fluid-discharge opening. 110

5. In a pump, the combination with a barrel, of a head fitted snugly within the barrel, a fluid-supply pipe extending longitudinally down into the barrel and connected to the head, and an upstanding liquid-discharge nozzle carried by the head and projecting into the barrel, said head having an orifice communicating with the supply-pipe, extending longitudinally of the barrel, and communicating therewith below the upper end of the nozzle. 125

6. In a pump, the combination with a bar- 130

rel, of a fluid-supply pipe extending longitudinally down through the barrel, a plurality of upwardly-extending liquid-discharge nozzles surrounding the pipe, and a device connected to the supply-pipe and having a plurality of upwardly-discharging orifices communicating with said pipe and terminating below the upper ends of the discharge-nozzles, said orifices communicating directly with the barrel.

7. In a pump, a barrel, a head located in and extending across the barrel, said head having a plurality of upwardly-extending discharge-nozzles terminating in the barrel and being also provided with a plurality of longitudinally-disposed discharge-orifices located contiguous to the nozzles, and a supply-pipe connected to the head and having communication with the discharge-orifices.

15 8. In a pump, the combination with a barrel, of a head located therein and having an annular series of liquid-discharge openings therethrough, a plurality of upwardly-extending discharge-nozzles mounted on the head and communicating with the openings, said head also having a plurality of upwardly-extending fluid-discharge openings, and a supply-pipe extending longitudinally into the barrel and secured to the head, said 30 pipe extending into the space between the nozzles and communicating with the fluid-discharge openings.

9. In a pump, the combination with a barrel, of a plurality of upwardly-extending discharge-nozzles communicating with and terminating within the interior of the barrel, of means for directing a plurality of separate jets of fluid under pressure upwardly within the barrel and longitudinally of said nozzles, 40 said means including a device having a plurality of discharge-orifices below the upper ends of the nozzles.

10. In a pump, a barrel located therein, a liquid-chamber located in the barrel, a valved inlet having a liquid-chamber, a head constituting the top of the liquid-chamber and having upwardly-extending liquid-outlets, said head also having fluid-outlets, a fluid-chamber communicating with the outlets, 50 said chamber being carried by the head and depending within the liquid-chamber, and a pipe connected to the head for supplying fluid under pressure to the fluid-chamber.

11. In a pump, the combination with a head having fluid and liquid outlets, of a standing valve member, a tubular connection between the head and member forming therebetween a liquid-chamber with which the liquid-outlets communicate, said chamber having an inlet through the standing valve member, a fluid-chamber having com-

munication with the fluid-outlets, and means for supplying fluid under pressure to the chamber.

12. In a pump, the combination with a barrel having a seat, of a liquid-chamber having a lower member that snugly fits upon the seat and has a lower inlet, a head for the liquid-chamber having liquid-outlets communicating with the chamber, and means for directing upward jets of fluid under pressure into the barrel above the head and chamber to effect the upward movement of the liquid from the chamber through the outlets.

13. In a pump, the combination with a barrel, of a fluid-supply pipe located therein, a head carried by the lower end of the supply-pipe and arranged in the barrel, said head having liquid and fluid outlets, the latter communicating with the pipe, the former extending through the head, a standing valve member located below the head, and a tubular connection between the head and standing valve member.

14. In a pump, the combination with a barrel having a seat in its lower portion, of a standing valve member that engages the seat, a tubular casing connected to the standing valve member and extending above the same within the barrel, a head secured to the upper end of the tubular casing, said head having liquid-outlets extending therethrough and being also provided with upwardly-extending fluid-outlets, and a fluid-supply pipe connected to the head and communicating with the fluid-outlets.

15. In a pump, the combination with a barrel having a tapering seat in its lower portion, of a standing valve member including a tapering plug that engages in the seat and a depending tube-section that projects therethrough, a tubular casing secured to the standing valve member and extending above the same, a head connected to the upper end of the tubular casing and having openings therethrough, upwardly-extending nozzles carried by the head and projecting above the same, a fluid-chamber carried by the head and extending within the tubular casing, said head having upwardly-extending fluid-discharge openings communicating with the chamber, and a supply-pipe connected to the head and communicating with the fluid-chamber.

In testimony that I claim the foregoing as my own I have hereto affixed my signature in the presence of two witnesses.
